UNITED STATES PATENT OFFICE.

WILLIAM JAMES COOKE, OF AUCKLAND, NEW ZEALAND, ASSIGNOR OF ONE-TENTH TO CHRISTOPHER DAVIS, ONE-TENTH TO WILLIAM JOHN FOOTE, ONE-TENTH TO WILLIAM PEARCE, ONE-TENTH TO FANNY COOKE, AND ONE-TENTH TO THOMAS ASHTON, ALL OF AUCKLAND, NEW ZEALAND.

ROTARY RAZOR-STROP.

1,357,956.

Specification of Letters Patent. Patented Nov. 9, 1920.

Application filed January 26, 1920. Serial No. 353,972.

To all whom it may concern:

Be it known that I, WILLIAM JAMES COOKE, a citizen of the Dominion of New Zealand, and residing at 56 Edenvale road, 5 Auckland, in the Provincial District of Auckland, New Zealand, a subject of the King of Great Britain and Ireland, have invented certain new and useful Improvements in Rotary Razor-Strops, of which the following is a specification.

This invention relates to razor strops of the rotary type, and provides a strop whereby both sides of the edge of a razor blade are stropped simultaneously.

15 Strops have been made whereby razor blades with two edges have been stropped simultaneously upon the same side only of the blade. Such a method of stropping is mechanically defective, and results in a bur 20 being left upon both edges.

The invention comprises rollers covered with leather or other suitable abrading surfaces, and arranged parallel to each other in a main frame or casing. The rollers are 25 geared together by spur wheels and are rotated by a handle which is prevented from being turned the wrong way by a ratchet wheel and pawl. One roller is mounted in bearings fixed to the sides of the main frame, 30 and the other roller is mounted in a frame pivoted to the interior of the main frame. The spindle of the said other roller projects through curved slots in the sides of the main frame. A tension spring, attached at one 35 end to the pivoted frame, is attached at its other end to a screw, which passes through the end of the frame and is provided with a thumb nut.

The blade to be sharpened is held in a 40 clip, which rests upon a leather strip let into recesses formed in the tops of the sides of the main frame.

The invention may be advantageously and 45 conveniently carried into practice as illustrated in the accompanying drawing, wherein:—

Figure 1 is a side elevation,

Fig. 2 a plan,

Fig. 3 a longitudinal sectional elevation,

50 and

Fig. 4 a cross section of the strop,

Fig. 5 is a perspective view of the clip.

The rollers 1 and 2 having abrading sur-

faces 3, are fixed to spindles 4 and 5 respectively, and are normally geared together 55 by spur wheels 6 and 7. The spindle 4 is mounted in the sides of a main frame 8 and is provided with a crank handle 9. The spindle 5 is mounted in a frame 10 pivoted upon a pin 11, and the ends of the said 60 spindle 5 project into slots 12 formed in the sides of the frame, the center from which the slots are struck co-incident with the center of the pin 11.

A tension spring 13 is attached at one end 65 to the bottom of the frame 10, and at its other end is attached to a screw 14, which passes through the end of the frame 8, where the said screw is provided with a thumb nut 15.

The blade 16 to be sharpened is held in a 70 clip comprising a bar 17 having a recess wherein the top of the said blade may lie. The blade is retained by pins 18 projecting from the face of the recess, and adapted to 75 engage notches formed in the ends of the blade. A keeper 19, pivoted at one end to the bar 17 by a pin 20, is adapted to be retained at its other end by a catch 21 fixed to the bar 17.

A ratchet wheel 24 on the spindle 4 and a spring pawl 25 pivoted on the main frame 8, prevent the handle 9 from being turned the wrong way.

The blade 16 having been placed in the 85 recess, engaged by the pins 18, and retained by the keeper 19, the clip is placed upon bearing surfaces 22 of leather let into recesses 23 formed in the tops of the frame 8, the rollers 1 and 2 having been previously 90 separated by turning the frame 10 on its pivot pin 11, to allow the edge of the blade to pass between the rollers. The frame 10 is then released, allowing the spring 13 to press the rollers 1 and 2 against the edge 95 of the blade, and the spur wheels 6 and 7 to mesh together. The handle 9 is then turned clockwise, while the clip and blade are held in position, the wheels 6 and 7 turning the roller 2 anti-clockwise. The edges on both 100 sides of the blade are thus sharpened simultaneously and without leaving bur.

The clips are made to suit blades of different shapes and depths, so that the edges of the blade are correctly presented to the 105 rollers.

The tension of the spring 13 is regulated by the nut 15.

What I do claim and desire to secure by Letters Patent of the United States is:—

- 5 A razor stropping machine comprising an inclosing casing, a stropping roller mounted on a shaft journaled in the sides of said casing, a second roller mounted on a shaft having its ends projecting through slots in
- 10 the casing, a frame within the casing having a horizontal base and uprights in which one

of the said roller shafts is journaled, a pivot for the frame extending through the casing and a tension device attached to the middle of the horizontal base of the frame and 15 one end of the casing.

In testimony whereof I affix my signature in the presence of two witnesses.

WILLIAM JAMES COOKE.
